UNITED STATES PATENT OFFICE.

JAMES T. GRIFFIN, OF OAK PARK, AND CARL A. NELSON, OF CHICAGO, ILLINOIS, ASSIGNORS TO WESTERN ELECTRIC COMPANY, INCORPORATED, OF NEW YORK, N. Y., A CORPORATION OF NEW YORK.

ABRADING MACHINE.

Application filed October 15, 1920. Serial No. 417,217.

This invention relates to abrading machines, and more particularly to an apparatus which is designed to remove the glaze from carbon disks used in granular transmitters, the removal of which results in giving the carbon button a surface which is better adapted to receive a copper plating to which they are subsequently treated.

The object of this invention is to provide a mechanism by means of which the operation of removing the glaze from carbon buttons may be rapidly and efficiently performed with a minimum of manual operation, thereby eliminating a difficult and objectionable hand rubbing operation and reducing to a minimum the loss in the number of buttons chipped or broken.

In connection with this mechanism there is provided a holder for the buttons while being operated upon which prevents breaking and chipping of the buttons during the operation and which can be rapidly and efficiently loaded and positioned on the mechanism during its operation.

In its preferred form the mechanism of this invention consists in general of a sand-blasting mechanism including a reciprocating table adapted to receive especially designed holders for the buttons. Indexing mechanism is provided for moving the table around under the sand-blasting nozzle. The holders are each provided with a number of radial rows of openings which receive the buttons.

In the drawings:

Fig. 1 is a partial front elevation of the apparatus with the cabinet enclosing it shown in section;

Fig. 2 is a partial plan section thereof with the cabinet in section;

Fig. 3 is a plan section taken on the line 3—3 of Fig. 1;

Fig. 4 is an enlarged plan section taken on the line 4—4 of Fig. 1;

Fig. 5 is a schematic view partly in section of the siphon system for feeding sand to the sand nozzle and of the air agitator scheme at the sand supply;

Fig. 6 is an enlarged plan view of the

reciprocal and intermittently revolvable table shown partly loaded with holders;

Fig. 7 is a section on the line 7—7 thereof, and

Fig. 8 is an enlarged detail section through one opening in the holder with a button held therein.

As shown in the drawings, 10 represents a bench or table provided with legs 11—11 for supporting the apparatus. Within a main enclosing cabinet 12 is a circular table 13 which is revolvably supported upon a shaft 14 secured to a reciprocal carrier 15. The carrier 15 rides between rollers 18—18 which are suitably secured to a frame 19 which in turn is secured to the cabinet 12. One portion of the carrier 15 is channel shaped in cross-section, as best shown in Fig. 4 at 20, which section provides a suitable surface for securing the shaft 14 thereto and makes the travel thereof while riding between the rollers 18—18 steadier. The other portion of the carrier 15 designated at 21 is circular in cross-section and is provided near its end with a slot 22.

The mechanism for reciprocating the table 12 will now be described.

Supported upon a shelf 23 secured between the legs 11—11 and to one side of the main cabinet 12 is a motor 25 which drives a worm gear 26 through a worm 27 secured upon its shaft. The worm gear 26 turns a suitable heart-shaped cam 28 which operates a cam rod 29 equipped with a roller 30 riding on the face of the cam 28. The rod 29 is pivoted at 31 to a bracket 32 secured to the under side of the table 10 with its upper end protruding through a slot 34 therein and is equipped with a roller 35 which rides in the slot 22 in the carrier 15. The slotted end of the carrier 15 is reduced and enters a compression spring 36 which is located within a case 37 secured to the cabinet 12. The spring 36 functions to return the parts to their normal position after a movement, as shown by the full line position thereof in Fig. 1. The case 37 is suitably slotted along its lower surface to provide for the movement of the cam rod 29.

The mechanism for indexing the table 13 carrying button holders 39-39 a distance from one row of buttons held therein to the next row at the end of a complete reciprocation of the table 13 consists of a ratchet wheel 40 secured to the under side of the table 13 which is engaged by a pawl 41 pivoted to a stationary support 42 and held in engagement with the teeth on the ratchet wheel 40 by a leaf spring 43. (See Fig. 3.)

The operation of the table reciprocating and indexing mechanism is as follows:

As the cam 28 is revolved, the cam rod 29 is rocked about its pivot 31 by the engagement of the roller 30 thereon with the face of the cam 28. The engagement of the roller 35 on the upper end of the cam rod 29 in the slot 22 of the carrier 15 causes the table 13 to be moved to the right, or to the dotted line position, as best shown in Fig. 3 and against the action of the spring 36. During this movement of the table 13 the row of buttons which are directly under the sand blast nozzle are given a blast and during the return movement they are also blasted. Near the end of the return movement the pawl 41, which has been moved inward about its pivot during the first part of the movement of the table by the spring 43 as the tooth which was engaged thereby was moved away, is moved inward against a stop 44 which brings the pawl in line to engage the next tooth on the ratchet in a counterclockwise direction. As the table nears the end of its complete movement or back to its normal position, as shown in Fig. 3, the pawl 41 engages a tooth in the ratchet, and as the table is still moving it is revolved to bring the next row of buttons under the sand blast nozzle in the direction indicated by the arrow in Fig. 3. In operation the cam 28 is continuously revolving so that the table is being continuously reciprocated back and forth and indexed to the next row of buttons receiving two blasts from the sand blast nozzle during a complete reciprocation.

The holders 39-39 are designed so that they may be readily loaded and placed in line on the table 13 or taken therefrom during the movements of the carrier, also the carbon buttons are held therein in such a manner that they are fully protected from being broken or chipped at their edges by being held in the holders, or by the sand blast. Each holder 39 consists of an arc shaped plate 46, the peripheral edge of which is of the same curve as the circumferential edge of the table 13 and is provided with four radial rows of openings 50 for the reception of the buttons. The walls of the openings 50 are tapered (see Fig. 8) and are a trifle smaller than the size of the button at one side of the plate. When the button is in place, the edge of the side

thereof which faces the sand blast is fully protected from being chipped thereby by that portion of the tapered wall which overhangs the edge of the button, as clearly shown in Fig. 8. The holders are preferably loaded by scooping the plate 46 upside down into a supply of buttons and shaking it until the openings 50 are all loaded. A support 51 equipped with a sponge rubber backing 52 which is of the same shape as the plate 46 is laid against the buttons in the openings therein and clamped thereto by turning thumb nuts 53 onto threaded pins 54 secured to the plate 46. The sponge rubber backing prevents the breaking of the buttons when the support 51 is clamped to the plate 46. The table 13 is provided with a depressed surface 55 provided with circular depressions 56 therein for the reception of the thumb nuts 53. The thumb nuts 53 entering the depressions 55 serve to retain the holders in position on the table 13 when it is being operated and also serve as locating means for the operator in placing the loaded holders in position on the table during its operation.

The air siphon system for drawing the sand combined with the air agitator at the sand supply consists of an air supply line 58 of a suitable size and provided with a suitable air pressure which is connected with both air siphon nozzle 59 and air agitator nozzle 60. A main valve 61 is provided for controlling both nozzles and an auxiliary valve 62 is placed in the line to the nozzle 59 so that the air thereto can be controlled independently of the air to the agitator nozzle 60. The nozzle 59, as clearly shown in Fig. 5, is of a suitable diameter and is secured within a fixture 63 which is adapted to be connected with the air line 58 and a line 64 to a sand supply fixture 65. A sand blast nozzle 66 is threaded onto a reduced end of the fixture 63 with the air nozzle 59 extending a short distance into the sand blast nozzle 66 to give the correct siphoning effect. The end of the sand blast nozzle 66 is surrounded by a suitable baffle 67 which is secured to the cabinet 12, as shown in Figs. 1 and 2, and is preferably made of sheet metal lined with rubber, the rubber being fringed as shown at its lower edge. A sand chute 69 is positioned under the reciprocating table 13 and the cabinet 12, being secured to the table 10. The sand after being blasted from the sand blast nozzle 66 falls down the chute 69 into the sand supply fixture 65.

The air agitator nozzle 60 which is connected with the air line 58 is suitably positioned within the fixture 65 with its upper end preferably located a suitable distance below the sand level indicated by broken line 72. The nozzle 60 is set in the fixture 130

65 at the same angle as the sand line 64 and in line with its center, thereby facilitating the siphoning of the sand by the air nozzle 59, and also tending to keep the sand in a loose condition suitable for use. The operator will throw into the chute 69 sufficient sand whenever it falls below the proper level. This is done by using suitable hand hole openings provided in the 10 front wall of the cabinet 12 (not shown in the drawings) which are used by the operator to load and unload the table 13 with the holders 39-39. A screen 73 is secured in the chute 69 so as to insure against large 15 particles getting into the sand supply fixture 65.

An exhaust duct 74 is located at the top of the cabinet 12 and near the back for drawing off dust, etc., which is created during sand blasting.

What is claimed is:

1. In a sand blasting apparatus, a work carrier for holding an article to be sand blasted, means for directing a sand blasting medium on the article when in a predetermined position, means for rotating said carrier to bring said article into said predetermined position, and means for effecting relative radial movement between said carrier and said first recited means while said article is in said position and during its subjection to said sand blasting medium.

2. In a sand blasting apparatus, a work carrier for holding a plurality of articles to be sand blasted, mechanism for directing a sand blasting medium on an article when in a predetermined position, means for rotating said carrier to successively bring said articles into said predetermined position, and means effective for reciprocating said carrier contemporaneously with the subjection of said article to said sand blasting medium.

3. In a sand blasting apparatus, a work carrier for holding an article to be sand blasted, means for directing a sand blasting medium on the article when in a predetermined position, means for intermittently rotating said carrier for bringing said article into said predetermined position, and means for effecting relative radial movement between said carrier and said first recited means while said article is in said position and during its subjection to said sand blasting medium.

4. In a machine for removing glaze from the surface of carbon buttons, a plurality of work holders each adapted to hold a number of rows of buttons, an intermittently rotatable and reciprocal carrier adapted to be loaded and unloaded and to retain said work holders thereon during movements thereof, and means for abrading the surfaces of one row of carbon buttons during each reciprocation of said carrier.

5. In a machine for removing glaze from the surface of carbon buttons, a plurality of work holders each adapted to hold a number of radially disposed rows of buttons, an intermittently rotatable and reciprocal carrier adapted to be loaded and unloaded and to retain said work holders thereon during movements thereof to cause each row of buttons to be treated twice with an abrading means before said carrier is revolved for the treatment of the next row of buttons, and means for abrading the surfaces of one row of carbon buttons during each reciprocation of said carrier.

6. In a machine for removing glaze from the surface of carbon buttons, a plurality of work holders each adapted to hold a number of rows of buttons and equipped with positioning and retaining means on their lower surfaces, an intermittently rotatable and reciprocal carrier provided with depressions on its upper surface for the reception of the positioning and retaining means on said work holders whereby said holders are adapted to be put on, taken off and retained on said carrier during movements thereof, and means for abrading the surfaces of one row of carbon buttons during each reciprocation of said carrier.

7. In an abrading apparatus, the combination with a work support and an abrading means, of a work holder comprising a plate provided with a plurality of openings adapted to receive the articles to be abraded and position them therein, said openings having a shape which will expose the entire top surface of the articles to the abrading means and protect the edges thereof from being chipped by said abrading means, and retaining means for holding the articles within the openings in said plate.

8. In an apparatus for removing glaze from the surface of carbon buttons, the combination with a work support and an abrading means, of a work holder comprising a plate provided with a plurality of openings with tapered walls adapted to receive the buttons and position them therein whereby the entire top surface is exposed to the abrading means with the edge thereof protected from being chipped by the overhanging tapered wall of the opening, and retaining means for holding the buttons within the openings in said plate adapted to be secured thereto.

9. In an abrading machine, a plurality of work holders each adapted to hold a number of rows of articles to be abraded, a carrier adapted to detachably hold said work holders, means for intermittently rotating and reciprocating said carrier, and means for abrading the surface of one row of said articles during each reciprocation of said carrier.

10. In an abrading machine, a plurality

of work holders each adapted to hold a number of radially disposed rows of articles to be abraded, a carrier adapted to detachably hold said work holders, means for intermittently rotating and reciprocating said work carrier, and means for abrading the surface of one row of said articles a plurality of times during each reciprocation of said carrier.

In witness whereof, we hereunto subscribe our names this 21 day of September A. D. 1920.

JAMES T. GRIFFIN.
CARL A. NELSON.
